ATOMIZER

Lewis W. Heller, Yardley, Pa., assignor to The Babcock & Wilcox Company, Rockleigh, N. J., a corporation of New Jersey

Application September 10, 1949, Serial No. 115,013

16 Claims. (Cl. 299—120)

This invention relates to variable capacity, pressure atomizing liquid fuel burners in which the liquid fuel is delivered to a circular whirl chamber under pressure, through substantially tangentially arranged slots, for discharge from an axial orifice in a hollow-cone spray. The invention is particularly applicable to such burners of the return flow type in which a variable quantity of the fuel is withdrawn from the whirl chamber and returned to its source or to some point in the fuel supply system.

Mechanical atomizing burners of this general type are well known and have been widely used where it is desired to handle a variable load by varying the capacity or fuel delivery rates to the burners rather than by varying the number of burners in operation. Return flow mechanical atomizing burners of this type have been used with several systems of operation. In one system, the supply pressure is maintained substantially constant and the return flow pressure is varied to regulate the amount of fuel bypassed. In another system, the supply pressure is varied and a substantially constant differential is maintained between the supply and return flow pressures. Still another system, which is described more particularly in the co-pending application of Thomas B. Stillman, filed September 8, 1949, for "Liquid Fuel Circulating System for Mechanically Atomizing Liquid Fuel Burner and Method of Controlling the Output of said Burner," now Patent No. 2,702,590, issued February 22, 1955, concurrently varies both the supply and return flow pressure whereby a varying differential between supply and return flow pressures is effected in attainment of a regulation of the fuel delivery rate through a wide capacity range.

In return flow burners, the amount of by-passed fuel can be controlled by a control valve located in the return flow passage and controlling the return flow pressure. If it is desired to operate as a straight mechanical atomizer, its control valve can be completely closed so that all the fuel is discharged through the orifice.

The most important operating features of a pressure atomizing liquid fuel burner, in addition to its range of capacity, are its variation in spray angle and the quality of atomization. A constant spray angle is desirable to insure complete and efficient combustion at all capacities by precluding the danger of furnace wall carbonization, furnace hot spots, or contact with the burner parts. It has been found that the spray angle tends to increase with a decrease in the amount of liquid fuel discharged from the atomizer orifice. A fine quality of atomization under all operating conditions is essential to insure rapid, uniform and complete vaporization and combustion. The wider range of capacity attainable with return-flow atomizers is frequently at the expense of spray angle variation and quality of atomization.

The present invention is directed to an improved arrangement for withdrawing liquid fuel from the whirl chamber whereby fuel leaving the chamber has a minimum impedance imposed upon its flow, and has a minimum disturbing effect upon the fuel whirling in the whirl chamber. To this end, the withdrawal means is so ar-

2

ranged as to provide for fuel flow thereinto, from the whirling mass of fuel, with substantially no change in the flow direction of the withdrawn fuel or interruption to its whirling motion. More specifically, an annular slot or passage opens into the whirl chamber rearwardly of the oil inlet passages, and the flow direction into such slot or passage is substantially normal to the lateral confining surface of the whirl chamber at the withdrawal zone. The cross sectional area of the slot or passage increases rapidly in a direction outwardly from the whirl chamber by virtue of the fact that the passage is essentially frusto-conical, diverging rearwardly relative to the whirl chamber axis, and the walls of the passage diverge from each other in a rearward direction. As a result, the velocity head of the withdrawn fuel is rapidly transformed into an increase in the static pressure head of the fuel. The withdrawn fuel consequently enters axially directed openings, connecting the annular passage to an axial return flow conduit at a very substantially reduced velocity. As a result of the foregoing, the withdrawal of the fuel has a minimum disturbing effect of the fuel whirling in the whirl chamber.

Preferably, the rear portion of the whirl chamber is spherically concave but, for practical manufacturing reasons, is generally made frusto-conical and rearwardly converging. However, if desired, the whirl chamber rear portion may be made uniform in cross sectional area or even rearwardly diverging. The portion of the whirl chamber at the intersection of the tangential inlet passages is cylindrical and merges smoothly with a frusto-conical section terminating at the axially or centrally arranged discharge orifice.

It is an object of the present invention to provide, in a pressure atomizing liquid fuel burner of the return flow type, an improved return-flow or by-pass arrangement assuring greatly reduced impedance to the fluid movement in the whirl chamber, particularly adjacent the return-flow portion.

Another object is to provide a novel whirl chamber configuration effecting improved quality of atomization and improved spray angle variation.

A further object is to provide a novel whirl chamber configuration which contributes to effective utilization of the liquid fuel entry velocity in maintaining maximum angular velocity conditions.

These and other objects, advantages and novel features of the invention, will be apparent from the following description and the accompanying drawings. In the drawings:

Fig. 1 is an elevation view, partly in section and broken along its length, of a liquid fuel burner according to the present invention;

Fig. 2 is an enlarged axial sectional view through an atomizer assembly according to the invention;

Fig. 3 is an enlarged axial sectional view of the atomizer assembly shown in Fig. 1;

Fig. 4 is an elevation view of the furnace face of a primary nozzle or plug member of the atomizer assembly of Figs. 1 and 3;

Fig. 5 is a longitudinal sectional view on the line 5—5 of Fig. 4;

Fig. 6 is an elevation view of a secondary nozzle of the atomizer assembly of Figs. 1 and 3;

Fig. 7 is a diametric sectional view on the line 7—7 of Fig. 6; and

Fig. 8 is a sectional view, on the line 8—8 of Fig. 3, of a sprayer or orifice plate of the atomizer assembly.

In the liquid fuel burner illustrated in Fig. 1, the atomizing parts are disposed within a tube or distance piece 10 having its furnace, forward, or discharge end normally positioned in or adjacent a fuel burner port of the furnace wall. If desired, tube 10 may be flared

and carry an impeller plate 11. In the particular burner shown by way of example only, the outer end of the distance piece may be threaded into a coupling 12 in which is formed a pair of parallel passages 13 and 14 serving as the liquid fuel supply and return flow passages, respectively. The coupling passages register with corresponding passages 15 and 16 in a body member 17 when coupling 12 is secured to member 17 by a coupling yoke 18 adapted to be held in its closing position by a T-handle set screw 19. The described burner construction is exemplary only, and the invention principles are applicable equally to other burners differing in construction from that shown.

The fuel supply and return flow passages 15, 16 of coupling member 17 are connected, respectively, to conduits or tubes 21 and 22 threadedly connected to the atomizer head or assembly. Tube 21 is concentric with and of larger diameter than tube 22 so that the tubes form an annular fuel supply passage 20, between tubes 21 and 22, and a central return flow passage 25 within tube 22. The furnace or inner ends of passages 20 and 25 communicate with the fuel supply and return flow portions, respectively of the pressure atomizing head or assembly 30.

In accordance with the present invention, it has been found that high quality atomization over a wide range, together with adequate control of the width of the spray angle over a corresponding range, can be effected by a novel arrangement of the return flow take-off from the whirl chamber and further improved results can be obtained by providing a novel configuration for at least the rear portion of the whirl chamber. The return flow or take-off means is formed as an annular slot or passage opening into the lateral surface of the whirl chamber rearwardly of the liquid fuel inlet means thereto. The arrangement is such that the direction of flow into the take-off slot or passage is substantially normal to the lateral surface of the rear portion of the whirl chamber, and the cross sectional area of the take-off passage increases rapidly outwardly of the whirl chamber. To accomplish this, the general configuration of the take-off passage is frusto-conical and rearwardly diverging, the passage walls being defined by a pair of concentric frusto-conical sections having their conical or lateral surfaces in laterally spaced relation to define the take-off passage. The walls of the passage preferably diverge from each other in a rearward direction.

Preferably, the portion of the whirl chamber rearwardly of the tangentially arranged inlet passages is spherically concave to obtain a minimum wall area to volume ratio to reduce flow impedance. This preferred arrangement is shown in Fig. 2. For practical manufacturing reasons of simplicity and economy, however, the rear portion of the whirl chamber is made frusto-conical, as shown in Figs. 1 and 3 through 7, as the slight change in shape of the whirl chamber is more than compensated by the reduction in manufacturing costs and complexities. Under certain circumstances, however, the rear portion of the whirl chamber may be uniform in cross-sectional area or even rearwardly diverging.

Reference will be had first to the arrangement of Fig. 2 and, in the arrangement of Figs. 1 and 3 through 7, corresponding parts have been given the same reference characters primed. The furnace end of tube 22 is threaded into the rear end of a cylindrical primary nozzle or plug member 23 having a sealing contact with the ends of tubes 21 and 22. Primary nozzle 23 has an annular slot 24 in its furnace face connected by a circular series of passages 26 to annular fuel inlet passage 20. The furnace face of the primary nozzle also has a smaller diameter annular slot 27, defining a central, substantially frusto-conical protuberance 28 and connected by a circular series of apertures 29 to the central fuel outlet or return flow passage 25. For a purpose to be

described, the furnace face 31' of protuberance 28 is spherically concave.

The furnace face of primary nozzle 23, when atomizer 30 is assembled, contacts with the outer face of a secondary nozzle or inner tip member 40. The latter has a central passage 33 therethrough, defined by a spherically concave wall 34 which, with the spherically concave face 31 of protuberance 28, constitutes the outer or rearward, and substantially hemispherical portion of a mixing or whirl chamber 35. The wall of passage 33 is so related to protuberance 28 as to form therewith an annular slot or passage 36, around the protuberance and connecting the rear portion of whirl chamber 35 to slot 27. It will be noted that the general direction of slot 36 is substantially normal to wall 34, and that the slot is substantially frusto-conical and rearwardly diverging. Hence, the cross-sectional area of slot 36 increases rapidly rearwardly or outwardly from wall 34. An annular slot 37 is formed in the furnace face of secondary nozzle 40 in alignment with slot 24 and connected therewith by a circular series of short passages 38.

The furnace face of nozzle 40, beyond slot 37, contacts with the outer face of a sprayer, or orifice plate, or outer tip 50, which has a portion of its periphery cut away to provide a seat for an end cap 55 which is screwed on the outer tube 21 to hold the primary nozzle, secondary nozzle and sprayer plate in their desired assembled position. Sprayer plate 50 has a central cylindrical opening 42 aligned with passage 33 to form an intermediate portion of whirl chamber 35. Opening 42 is connected by a frusto-conical passage 43 to a discharge orifice 44 of smaller diameter than the whirl chamber 35. The outer face of sprayer plate 50 is formed with a plurality of slots 46 each tangential to passage or opening 42 and communicating, at their outer ends, with slot 37 of nozzle member 40.

With the foregoing construction, liquid fuel, such as oil, under a substantial pressure, is delivered to inlet passage 20 from which it passes through holes 26, slot 24, holes 38, and slot 37 into tangential slots 46 in orifice plate 50. Due to the tangential arrangement of slots 46, the oil follows a spiral path in whirl chamber 35 toward discharge orifice 44. If the atomizer is operated as a return-flow atomizer, a variable portion of the oil, dependent upon the relation between the supply and return pressures, follows a spiral path toward slot 36 from whence it passes through slot 27 and holes 29 into return flow passage 25.

The provision of the outwardly divergent, annular return-flow slot 36, having a flow direction substantially normal to the surface 34, results in substantial elimination of turbulence in the rear portion of the whirl chamber and in a smooth take-off of the return-flow liquid fuel, as there is no change in the flow direction of the withdrawn fuel. The substantially normal relation of slot or passage 36 to wall 34 provides for effective utilization of the centrifugal force of the whirling liquid fuel in directing the return flow into passage 36. The rearward or outward divergence of the annular passage 36 provides a rapid increase in the cross-sectional area of the passage outwardly of the whirl chamber. Consequently, the velocity head of the liquid fuel is correspondingly effectively reduced and converted into an increased static pressure head as the fuel flows outwardly through passage 36 into annular slot 27, from which it passes through passages 29 into return-flow passage 25 of tube or conduit 22.

The oil discharged through orifice 44 emerges as a spray of hollow, conical configuration and a substantially constant angle over a wide range of atomizer capacity. Due to the spherically concave shape of the outer or rear portion of whirl chamber 35 and the smooth withdrawal of the return-flow fuel, the oil is discharged from orifice 44 as a substantially uniform, whirling spray cone. When the atomizer is operated as a straight mechanical atom-

izer, with return flow passage 25 closed by a valve there is a substantially solid body or mass of oil in passage 25, holes 29, and slots 27 and 36. The effect is to provide a substantially non-interrupted, hemispherical surface for the rear or outer portion of the whirl chamber, resulting in a substantially non-turbulent discharge from orifice 44.

In the modified atomizer assembly 30' shown in Figs. 1 and 3 through 7, the inner end of tube 22 is threaded to engage a cylindrical primary nozzle or plug member 23' which is generally similar to nozzle 23 and has a sealing contact with the furnace ends of tubes 21 and 22. Nozzle 23', as best shown in Figs. 4 and 5, has an annular slot 24' in its furnace face connected by a circular series of passages 26 to annular fuel inlet passage 25. The furnace face of nozzle 23' also has a smaller diameter annular slot 27' defining a central, substantially frusto-conical protuberance 28' which projects beyond the forward face of the remainder of the nozzle 23'. Slot 27' is connected by a circular series of apertures 29' to the central fuel outlet or return passage 20. Protuberance 28' is frusto-conical and has a flat or plain furnace face 31'.

The furnace face of nozzle 23', when atomizer 30' is assembled, contacts with the outer face of a secondary nozzle or inner tip member 40', shown more particularly in Figs. 6 and 7. The latter has a central passage 33' therethrough, which is cylindrical. Toward the outer face of nozzle 40', passage 33' connects with a frusto-conical rearwardly diverging passage 53 and toward the furnace face of nozzle 40', passage 33' communicates with a frusto-conical forwardly diverging passage 34'. The wall of passage 53 is so related to protuberance 28' as to form an annular passage 36' around the protuberance and connecting whirl chamber 35' to slot 27'. An annular slot 37' is formed in the furnace face of secondary nozzle 40' in alignment with slot 24' and connected therewith by a circular series of short passages 38'.

The furnace face of nozzle 40', beyond slot 37', contacts with the outer face of a sprayer, or orifice plate or outer tip 50', best shown in Figs. 3 and 8. Orifice plate 50' has a portion of its periphery cut away to provide a seat for an end cap 55' which is identical with cap 55 and is screwed on outer tube 21 to hold primary nozzle, secondary nozzle, and sprayer plate in their desired assembled position. Sprayer plate 50' has a central cylindrical opening 42 forming a continuation of frusto-conical forward passage 34' to nozzle 40'. Opening 42' is connected by a frusto-conical forwardly converging passage 43' to a discharge orifice 44' of whirl chamber 45'. The outer face of sprayer plate 50' is formed with a plurality of slots 46', each tangential to passage or opening 42', and communicating at the outer ends with slot 37' of nozzle member 40'.

This embodiment of the atomizer assembly operates in the same manner as does that of the sprayer assembly shown in Fig. 2. The return flow liquid fuel is drawn off in a non-turbulent manner through the annular slot 36' at the rear of whirl chamber 35', which provides for fuel flow thereto without change in flow direction. The rear portion of the whirl chamber, in advance of slot 36' is substantially frusto-conical, thus being somewhat simpler as regards the manufacture of the atomizer assembly than is the spherical rear whirl chamber portion of Fig. 2. The rear wall of the whirl chamber is formed by the flat face 31' of protuberance 28' which cooperates with outer nozzle 40' to form the return flow slot 36'.

The diverging annular slot 27', formed by wall section 53 and the lateral surface of protuberance 28', has a general flow direction substantially normal to the frusto-conical surface 34' of the rear portion of whirl chamber 35'. Also, the cross-sectional area of slot 27' increases rapidly outwardly of chamber 35'. These features effect the improved performance in the same manner as does slot 27 of Fig. 2.

While specific embodiments of the invention have been

shown and described in detail to illustrate the application of the invention principles, it will be understood that the invention may be otherwise embodied without departing from such principles.

5 I claim:

1. A return-flow liquid fuel burner comprising, in combination, means forming a whirl chamber of circular cross section including a fuel inlet zone intermediate the length of the whirl chamber, a discharge orifice at one end thereof, and a rear wall; fuel supply passage means communicating tangentially with such inlet zone; means for removing a portion of the fuel whirling in such chamber comprising an annular return flow slot communicating peripherally with the rear wall of the chamber and increasing uniformly in diameter and cross-sectional flow area outwardly of the whirl chamber; and a return flow passage communicating with such return flow means.
2. A return-flow liquid fuel burner comprising, in combination, means forming a whirl chamber of circular cross section including a fuel inlet zone intermediate the length of the whirl chamber, a discharge orifice at the forward end thereof, and a rear wall; fuel supply passage means communicating tangentially with such inlet zone; means for removing a portion of the fuel whirling in such chamber comprising a return flow passage communicating with an annular slot opening through the rear wall of the chamber and diverging uniformly outwardly from the whirl chamber; and a return flow conduit communicating with such return flow passage.
3. A return-flow liquid fuel burner comprising, in combination, means forming a whirl chamber of circular cross section including a fuel inlet zone intermediate the length of the whirl chamber and a discharge orifice at one end thereof; a fuel supply passage communicating tangentially with such inlet zone; and means for removing a peripheral portion of the liquid fuel whirling in such chamber comprising a return flow passage opening through the surface of such chamber throughout the chamber circumference rearwardly of such inlet zone, such passage extending substantially normal to the lateral surface of the whirl chamber and increasing uniformly in diameter and cross-sectional area outwardly from such lateral surface.
4. A return-flow liquid fuel burner comprising, in combination, means forming a whirl chamber of circular cross section including a fuel inlet zone intermediate the length of the whirl chamber and a discharge orifice at one end thereof, the whirl chamber progressively decreasing in cross sectional area from such inlet zone to the opposite end of the whirl chamber; a fuel supply passage communicating tangentially with such inlet zone; and means for removing a peripheral portion of the liquid fuel whirling in such chamber comprising an annular return flow passage opening to such chamber through the surface of such opposite end and throughout the chamber circumference and increasing uniformly in diameter and cross-sectional area outwardly from such surface.
5. A return-flow liquid fuel burner comprising, in combination, means forming a whirl chamber of circular cross section including a fuel inlet zone intermediate the length of the whirl chamber and a discharge orifice at one end thereof, the whirl chamber decreasing in cross sectional area at a progressively increasing rate from such inlet zone to the opposite end of the whirl chamber; a fuel supply passage communicating tangentially with such inlet zone; and means for removing a peripheral portion of the liquid fuel whirling in such chamber comprising a return flow passage opening to such chamber through the surface of such opposite end and throughout the chamber circumference and increasing uniformly in diameter and cross-sectional area outwardly from such surface.
6. A return-flow liquid fuel burner comprising, in combination, means forming a whirl chamber of circular cross section including a fuel inlet zone intermediate the length of the whirl chamber and a discharge orifice at one end

thereof, the whirl chamber decreasing in cross sectional area substantially uniformly from such inlet zone to the opposite end of the whirl chamber; a fuel supply passage communicating tangentially with such inlet zone; and means for removing a peripheral portion of the liquid fuel whirling in such chamber comprising a return flow passage opening to such chamber through the surface of such opposite end and throughout the chamber circumference and increasing uniformly in diameter and cross-sectional area outwardly from such surface.

7. A return-flow liquid fuel burner comprising, in combination, means forming a whirl chamber of circular cross section including a fuel inlet zone intermediate the length of the whirl chamber, an axial discharge orifice at one end thereof, and a rear wall; a fuel supply passage communicating tangentially with such inlet zone; and means for removing a portion of the fuel whirling in such chamber comprising an annular return flow passage opening peripherally through such rear wall of the chamber rearwardly of the inlet zone; the radially inner and outer walls of said passage being at an acute angle to the axis of the whirl chamber.

8. A return-flow liquid fuel burner comprising, in combination, means forming a whirl chamber of circular cross section including a fuel inlet zone intermediate the length of the whirl chamber, an axial discharge orifice at one end thereof, and a rear wall; a fuel supply passage communicating tangentially with such inlet zone; and means for removing a peripheral portion of the liquid fuel whirling in such chamber comprising an annular return flow passage communicating with an annular slot opening through the rear wall of such chamber rearwardly of the inlet zone; the radially inner and outer walls of such passage being substantially normal to the wall of the chamber and at an acute angle to the axis of the chamber.

9. A return-flow liquid fuel burner comprising, in combination, means forming a whirl chamber of circular cross section including a fuel inlet zone intermediate the length of the whirl chamber, an axial discharge orifice at one end thereof, and a rear wall; a fuel supply passage communicating tangentially with such inlet zone; and means for removing a peripheral portion of the liquid fuel whirling in such chamber comprising a return flow passage communicating with an annular slot opening through the rear wall of such chamber rearwardly of the inlet zone and throughout the chamber circumference; the diameter and cross sectional flow area of such slot increasing rapidly and uniformly outwardly from the whirl chamber.

10. A return-flow liquid fuel burner comprising, in combination, means forming a whirl chamber of circular cross section including a fuel inlet zone intermediate the length of the whirl chamber and an axial discharge orifice at the forward end thereof, the surface of the whirl chamber rearwardly of the inlet zone being substantially hemispherical; a fuel supply passage communicating tangentially with such inlet zone; and means for removing a peripheral portion of the liquid fuel whirling in such chamber comprising an annular slot in such hemispherical surface rearwardly of such inlet zone and a return flow passage communicating with such slot.

11. A return-flow liquid fuel burner comprising, in combination, means forming a whirl chamber of circular cross section including a fuel inlet zone intermediate the length of the whirl chamber and an axial discharge orifice at the forward end thereof, the surface of the whirl chamber rearwardly of the inlet zone being substantially frusto-conical and decreasing in radius rearwardly of such inlet zone to a reduced diameter throat; a fuel supply passage communicating tangentially with such inlet zone; and means for removing a peripheral portion of the liquid fuel whirling in such chamber comprising an annular slot opening into such throat and having radially inner and outer walls diverging rearwardly from such throat, one of said walls being perpendicular to said frusto-conical surface, and a return flow passage communicating with such slot.

12. A spill burner comprising a hollow member defining a swirl chamber which is symmetrical about an axis, and having inlet orifices tangentially admitting to said chamber, an axially centered circular discharge orifice formed at one end of said swirl chamber, of a diameter small in comparison to the maximum diameter of the chamber itself, and an axially centered circular spill opening formed in the opposite end of said swirl chamber, a stem which is symmetrical about the swirl chamber's axis, means located wholly outside the swirl chamber to support said stem in position wherein it projects into the spill opening, said stem being of a shape and maximum diameter, in relation to said spill opening and to the discharge orifice, to define, in such position, a wholly uninterrupted annular spill orifice which is of capacity at least equal to the sum of the capacities of said tangential inlet orifices.

13. A spill burner comprising a hollow member defining a swirl chamber and a separate diffusing chamber each of which is symmetrical about and aligned along a common axis, said hollow member having inlet orifices tangentially admitting to said swirl chamber, an axially centered circular spill opening affording communication between the swirl chamber and the diffusing chamber, and an axially centered circular discharge orifice leading from the end of the swirl chamber which is distant from said spill opening, and of a diameter which is small with respect to both the maximum diameter of the swirl chamber and the minimum diameter of the spill opening, a stem which is symmetrical about the chambers' axis, supported entirely from that wall of the diffusing chamber which is opposite the spill opening, and projecting thence into the spill opening, said stem being of a shape and maximum diameter, in relation to said spill opening and to the discharge orifice, to define a wholly uninterrupted annular spill orifice which is of a capacity at least equal to the sum of the capacities of said tangential inlet orifices.

14. A spill burner comprising hollow means defining a swirl chamber of round cross-section having tangentially arranged inlet openings in its peripheral wall, a discharge orifice axially located at its forward end, and a rear wall opposite said discharge orifice, said rear wall being axially apertured, inwardly from the chamber's peripheral wall, to leave a surrounding annular portion as part of the rear wall, and an element supported rearwardly of said rear wall, projecting forwardly into its aperture, coaxially spaced within the margin of said aperture, and having its forward terminus forming part of the swirl chamber's rear wall, to define, in conjunction with the rear wall's aperture, a wholly uninterrupted annular spill orifice spaced inwardly from the swirl chamber's peripheral wall.

15. A spill burner comprising hollow means defining a swirl chamber of round cross-section having tangentially arranged inlet openings in its peripheral wall, a discharge orifice axially located at its forward end, and a rear wall opposite said discharge orifice, said rear wall having a single, circular, axially located discharge aperture, said hollow member being enlarged radially, rearwardly of said discharge aperture, to define a diffusing chamber located substantially wholly radially outwardly of said discharge aperture, an element ported for further discharge but otherwise closing and defining the rear end of said diffusing chamber, said element having an axially disposed forward extension projecting within the discharge aperture of the swirl chamber, spaced within the margin of such discharge aperture to define therewith an annular spill orifice which is wholly uninterrupted circumferentially, from the swirl chamber to the rear end of the diffusing chamber, and a capacity at least as great as the sum of the capacities of the tangential inlet openings.

16. A spill burner comprising hollow means having a cylindrical peripheral wall forming a swirl chamber having tangentially arranged inlet orifices, and a circular discharge orifice axially located in the forward end there-

of and of a diameter small in comparison to said cylindrical wall, said swirl chamber having also a rear wall closing the opposite end of said swirl chamber but having axially located therein a circular spill opening larger in diameter than said discharge orifice but smaller than the peripheral wall, a solid member of circular transverse section projecting into said spill opening in spaced coaxial relation therewith, from a location beyond the rear wall of said swirl chamber into the vicinity of such rear wall, said solid member defining in conjunction with said 5 spill opening, a continuous annular spill orifice of capacity at least as great as the sum of the capacities of said

10
5

inlet orifices, and located wholly outwardly of the axial projection of said discharge orifice.
